JOHN C. COLLIER, OF RUSSELTON, PENNSYLVANIA.

SAFETY-GATE FOR ELEVATOR-HATCHWAYS.

1,136,655.

Specification of Letters Patent.

Patented Apr. 20, 1915.

Application filed May 6, 1914. Serial No. 836,745.

To all whom it may concern:

Be it known that I, JOHN C. COLLIER, a citizen of the United States of America, residing at Russelton, in the county of Allegheny and State of Pennsylvania, have invented certain new and useful Improvements in Safety-Gates for Elevator-Hatchways, of which the following is a specification, reference being had therein to the accompanying drawing.

This invention relates to safety gates for elevator hatchways, more particularly mine hatchways, and has for its object to provide a gate of such class in a manner as herein-after set forth, which is automatically unlocked when the elevator car or hoist reaches a platform or landing, so that access can be had to the elevator car or hoist.

Further objects of the invention are to provide a safety gate and its operating mechanism which is simple in its construction and arrangement, strong, durable, efficient in its use, readily set up, and comparatively inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—Figure 1 is a top view illustrating the gate and the mechanism for unlocking the same, Fig. 2 is a front elevation of the gate being locked, Fig. 3 is a vertical sectional view of a hatchway illustrating a portion of the unlocking mechanism for the gate, and Fig. 4 is a perspective view illustrating the locked casing.

Referring to the drawings in detail, 5 denotes a landing, 6 a hatchway, and 7 and 8 a pair of vertical guides arranged at the landing and at opposite sides of the hatchway. The elevator car or hoist is indicated at 9.

Arranged within the landing are opposed fence posts 10 and 11 and opposed fence posts 12 and 13. The post 12 is parallel to the post 10 and the post 13 parallel to the post 11. The posts 12 and 13 are spaced

from the posts 10 and 11 and hinged as at 14 to the post 12 is a gate 15, and hinged as at 16 to the post 13 is a gate 17.

Arranged in proximity to the inner side of the posts 10 and 11 is an upright 18 provided at the top of one side thereof with a casing 19 having a hinged door 20, whereby access can be had to the interior of the casing. The outer side of the casing 19 is formed with a rectangular slot 21. The casings 19 extend parallel with the gates 15 and 17 when these latter are closed and the slots 21 in the casings 19 are provided for the entrance of flat apertured keepers 22, which are carried by and project inwardly from the gates 15 and 17 at the free sides thereof.

The guide 7 is provided with a recess 23 and an opening 24, which communicates with said recess 23, and arranged within the recess 23 is a bow-shaped resilient shifting member 25, which has its ends slidably connected to coupling pins 26 therefor. The pins 26 are carried by the guides 7.

Arranged within the passageway which forms a landing, is an oppositely disposed rock shaft 27, provided centrally with a crank 28, which is formed with a longitudinal slot 29 and extending through the latter is a pin 30 carried by the end 31 of an actuating member 32, the latter extends through the opening 24 and is connected to the member 25, and surrounding the member 32 between the upright 7 and member 25 is a coiled spring 37. The member 25 projects in the path of the elevator car or hoist 9, whereby the said car or hoist 9 will ride against said member 25 to force the same inwardly in the recess 23, and such action of the member 25 will force the member 32 rearwardly with respect to said recess 23, and shift the crank 28, thereby rocking the shaft 27 against the action of the spring 37 and resilient shifting member 25.

The rock shaft 27 extends through the top of the uprights 18 and into the casing 19, and the ends of said rock shafts terminate in crank arms 38 provided with a depending end 39. The depending ends 39 extend into the apertured keepers 22 for the purpose of locking the gates 15 and 17 in closed position. The crank arms 38 are shifted upwardly when the shaft 27 is actuated due to the moving rearwardly of the actuating member 32 and when said crank arms 38

are shifted upwardly, the ends 39 are moved out of the keepers 22 whereby the gates 15 and 17 are unlocked.

What I claim is:—

- 5 1. A safety gate for elevators comprising the combination with a gate provided with a keeper and a shaft having a crank arm formed with a depending end engaging in said keeper for maintaining the gate locked; of a resilient shifting member comprising a bulged leaf spring arranged in the path of a hoist, leaf spring 30 arranged in the path of a hoist, a lateral arm connected to the bulged portion of said spring, a coiled spring encircling said arm to force the leaf spring to its extended position and means operatively connecting the opposite end of said arm with said shaft to rock the latter as the hoist moves 35 passes said leaf spring.
- 10 2. In a device of the class described, the combination with a hatchway, a swinging gate carried on the frame thereof and provided with a keeper, the frame of said hatchway having a recess at a predetermined point therein and a shaft having a crank 40 point therein and a shaft having a crank arm formed with a depending end for engagement in said keeper to maintain the gate locked; of a resilient shifting member comprising a bulged leaf spring arranged in said recess in the path of a hoist, the free ends of said spring being movably connected to the frame of said hatchway to admit of compression of said spring, a lateral arm connected with the bulged portion of said spring and guided through the frame of said hatchway, a coil spring encircling said arm between said frame and the leaf spring to normally force the latter to its extended position, and means operatively connecting the opposite end of said lateral arm with said shaft to rock the latter as the hoist moves 45 passes the leaf spring.
- 15 3. In a device of the class described, the combination with a hatchway, a swinging gate carried on the frame thereof and provided with a keeper, the frame of said hatchway having a recess at a predetermined point therein and a shaft having a crank arm formed with a depending end for engagement in said keeper to maintain the gate locked; of a resilient shifting member comprising a bulged leaf spring arranged in said recess in the path of a hoist, the free ends of said spring being movably connected to the frame of said hatchway to admit of compression of said spring, a lateral arm connected with the bulged portion of said spring and guided through the frame of said hatchway, a coil spring encircling said arm between said frame and the leaf spring to normally force the latter to its extended position, and means operatively connecting the opposite end of said lateral arm with said shaft to rock the latter as the hoist moves 50 passes the leaf spring.
- 20 4. In a device of the class described, the combination with a hatchway, a swinging gate carried on the frame thereof and provided with a keeper, the frame of said hatchway having a recess at a predetermined point therein and a shaft having a crank arm formed with a depending end for engagement in said keeper to maintain the gate locked; of a resilient shifting member comprising a bulged leaf spring arranged in said recess in the path of a hoist, the free ends of said spring being movably connected to the frame of said hatchway to admit of compression of said spring, a lateral arm connected with the bulged portion of said spring and guided through the frame of said hatchway, a coil spring encircling said arm between said frame and the leaf spring to normally force the latter to its extended position, and means operatively connecting the opposite end of said lateral arm with said shaft to rock the latter as the hoist moves 55 passes the leaf spring.

Copies of this patent may be obtained for five cents each, by addressing the "Commissioner of Patents, Washington, D. C."

arm formed with a depending end for engagement in said keeper to maintain the gate locked; of a resilient shifting member comprising a bulged leaf spring arranged in said recess in the path of a hoist, the free ends of said spring being movably connected to the frame of said hatchway to admit of compression of said spring, a lateral arm connected with the bulged portion of said spring and guided through the frame of said hatchway, a coil spring encircling said arm between said frame and the leaf spring to normally force the latter to its extended position, and means operatively connecting the opposite end of said lateral arm with said shaft to rock the latter as the hoist moves 25 passes the leaf spring.

In testimony whereof I affix my signature in the presence of two witnesses.

JOHN C. COLLIER.
